UNITED STATES PATENT OFFICE.

JOHN KLINGE, OF DUBUQUE, IOWA.

ROTARY PUMP.

Application filed May 11, 1925. Serial No. 29,274.

This invention relates to rotary pumps for moving water, oil and various other liquids, and has as one of its objects to provide a mechanically actuated pump in which 5 valves of the usual type, and springs of any kind are wholly eliminated.

A further object is in the provision of an essentially compact, simple and efficient rotary pump capable of long and continuous 10 service.

Another aim is to provide a pump that can be cheaply constructed, all parts being of simple design.

These and like other aims and objects are 15 attained by the novel design, construction and combination of parts hereinafter fully described and shown in the accompanying drawing, forming an essential part of this disclosure, and in which:—

20 Figure 1 is a vertical sectional view of a rotary pump made in accordance with the invention.

Figure 2 is a similar view of the same, the parts being in a different position.

25 Figure 3 is a vertical sectional view, taken in a plane at a right angle to Figures 1 and 2, on line 3—3 of Fig. 1.

Figure 4 is a top plan view of the same.

30 Referring to the drawing in greater detail, the pump casing comprises upper and lower portions 13 and 12 having outer walls 10 and 11, and inner walls 14 and 15 separated by a spacing plate 16.

35 The upper portion 13 has bolted to it a combined inlet and outlet manifold 17 in which are engaged supply and discharge pipes 18 and 19 leading to chambers 20 and 21.

40 The chamber 20 has inlet openings 23 admitting the liquid to passages 24 and 25, below which are cylindrical piston chambers 26 and 27. The passages 24 and 25 are substantially rectilinear, and extend from piston chambers 26 and 27 to the inlet and outlet 45 openings of the casing, their directions being substantially radial with respect to chambers 26 and 27.

A shaft 28 is journalled axially of the piston chambers in the sides of the body 50 and fixed on the shaft are eccentrics 29 and 30 filling the spaces between the side walls 10 and 14, and 11 and 15 and being disposed in opposite relation.

55 Rotatable on the eccentrics are ring pistons 31 and 32, their peripheral surfaces being adapted to make wiping contact with

the walls of the piston chambers 26 and 27, as they are moved therearound by the eccentrics 29 and 30.

In the upper part of the casing are other 60 cylindrical bores 33 in which are rotatably fitted cylindrical valves 34, provided with rectilinear ports 35 of uniform cross section affording communication between the piston chambers 26 and 27 and outlet passages 36 65 leading to the discharge chamber 21 in the manifold. As will be seen from the drawing, each port 35 is adapted to assume a position in substantial alinement with the passage 36 during the greater part of the pumping stroke, to thereby permit the passage of liquid through the outlet passage without substantial change of direction. The purpose of this arrangement is to minimize eddying and consequent frictional 70 losses in the flow of the liquid.

Both of the valves 34 contain bored off center sockets 37 in which are mounted round bars 38 to freely pivot therein. Extending downwardly from the bars are 80 plates 39, their lower portions fitting transverse radial slots in the pistons 31 and 32 respectively, these plates forming partitions between the inlet and outlet passages.

85 In operation, power being transmitted to the shaft 28, the eccentrics are rotated causing the pistons to describe circuitous paths in contact with the walls of the chambers 26 and 27.

90 By reference to Figure 2 it will be seen that water or like liquid entering through the pipe 18 will be divided to pass in two streams through the inlet openings 23 to the passages 24 and obviously flow freely into the space between the walls of the pistons 95 and piston chambers, this space constantly varying in volume.

The piston 31, moving in counter-clockwise direction forces the water around itself, and eventually through the port 35, and 100 passage 36 into the chamber 21 and out of the pipe 19.

The other piston obviously operates in the same manner but in opposite phase, thereby producing a substantially regular and continuous flow through the pipe 19.

Having thus described my invention, what I claim as new and desire to secure by Letters Patent, is:—

1. A rotary pump comprising a pair of 110 similar body members having open upper chambers on one side of each body and cir-

cularly bored valve seats on the other side, a cover removably engaged over said members, said cover having inlet and outlet openings communicating respectively with the chambers and valve seat bores, said body having cylindrical bores in the main lower portions, a shaft passing axially through the last named bores, eccentrics fixed in opposed relation on said shaft, cylinders rotatable on said eccentrics, cylindrical valves in the mentioned valve seats, said valves each having tangential ports communicating with its corresponding chamber in said cover, said valves having bores adjacent their periphery parallel with their axes and grooves leading thereto, pivots operative in the bores of said valves, and plates on said pivots engaging radial slots in said cylinders, said plates transmitting rotary motion to said valves and serving as closures between the sides of the body members and for the ports in said valves.

2. In a rotary pump, the combination with a body having registering bored openings in its lower portion and similarly but smaller openings in its upper portion, a cover removably secured on said body, a shaft rotatable axially in the lower openings, eccentrics fixed on said shaft in opposed relation, rings revoluble on said eccentrics, their peripheral surfaces making wiping contact with the inner surfaces of the walls of the lower openings, valves rotatable in the upper openings, said valves having ports disposed in planes tangent to the axis of valve rotation, each of said valves having cylindrical openings disposed lengthwise at a point remote from the center, pivots rotatable in the valve openings, and plates fixed in said pivots to extend radially into slots in the periphery of said rings, said

plates acting as closures for the valve ports when in one position and as webs dividing the upper portion of said body.

3. A rotary pump for liquids, comprising a casing having a cylindrical piston chamber and substantially rectilinear inlet and outlet passages communicating therewith, an eccentric ring piston in said chamber, a cylindrical member rotatably mounted in said outlet passage, and a partition plate pivoted to said cylindrical member and fixed to said piston, said cylindrical member being provided with a rectilinear port adapted to assume a position in substantial alignment with said outlet passage during the greater part of the pumping stroke, to permit the passage of liquid from said chamber through said outlet passage without substantial change of direction.

4. A rotary pump for liquids, comprising a casing having adjacent inlet and outlet openings, a cylindrical piston chamber, and substantially rectilinear inlet and outlet passages extending radially from said piston chamber to said openings, an eccentric ring piston in said chamber, a cylindrical member rotatably mounted in said outlet passage, and a partition plate pivoted to said cylindrical member and fixed to said piston, said cylindrical member being provided with a substantially rectilinear port of uniform cross-section adapted to assume a position in substantial alignment with said outlet passage during the greater part of the pumping stroke, to permit the passage of liquid through said outlet passage without substantial change of direction.

In witness whereof I have affixed my signature.

JOHN KLINGE.
